UNITED STATES PATENT OFFICE.

THOMAS HALL, OF JERSEY CITY, NEW JERSEY.

DESIGN FOR A SHOW-CARD FOR HEAD-NETS.

Specification forming part of Design No. 6,341, dated January 14, 1873.

To all whom it may concern:

Be it known that I, THOMAS HALL, of Jersey City, in the county of Hudson and State of New Jersey, have invented a new and original Design for Pattern-Cards, of which the following is a specification:

The object of the card is to support and display ladies' hair-nets in a tasteful and attractive manner.

The drawing represents a face view of my new design for pattern-cards.

This invention relates to a new design for pattern-cards; and consists in making the

same in form of a shield, of the outline shown in the drawing. This shield has a double-ogee outline at the upper edge, a single-ogee outline at each side, and a double-ogee lower edge, all as clearly shown in the drawing.

The card is made of pasteboard or other material, and of suitable size.

I claim as my invention—

The design for the shield-shaped pattern-cards, as described.

Witnesses: THOMAS HALL.
